UNITED STATES PATENT OFFICE.

GEORG BRANDSTETTER, OF HOHENSTADT, AND RICHARD FREUND, OF VIENNA,
AUSTRIA-HUNGARY.

PNEUMATIC PILE-FEEDER.

1,178,293.

Specification of Letters Patent.

Patented Apr. 4, 1916.

Application filed September 15, 1913. Serial No. 789,826.

To all whom it may concern:

Be it known that we, GEORG BRANDSTETTER and RICHARD FREUND, subjects of the Emperor of Austria-Hungary, residing at 5 Hohenstadt, Moravia, and Vienna, both in the Empire of Austria-Hungary, have invented certain new and useful Improvements in Pneumatic Pile-Feeders; and we do hereby declare the following to be a full, clear, 10 and exact description of the invention, such as will enable others skilled in the art to which it appertains to make and use the same.

Our invention relates to automatic pile 15 feeders for printing presses.

The object of our invention is to avoid the various deficiencies to be met with in apparatus of this class as heretofore constructed.

In the drawings Figures 1 and 3 are side 20 elevations of our improved apparatus viewed from opposite sides. Fig. 2 is a vertical section. Fig. 4 is a front elevation partly in section, Fig. 5 is a sectional plan view and Fig. 6 shows diagrammatically the arrangement of air pipes and cocks.

Our improved pile feeder comprises two standards *a* mounted on the side frames of the press and connected with each other by a transverse beam *b* and a shaft *c* carrying 30 at each of its ends a plurality of cams controlling the operation of various parts as hereinafter more fully described and driven by a sprocket wheel *d* in synchronism with the printing press. The crank disk *e* actuates through the medium of a link *f*, a lever *g*, the free end of which is connected by a link *h* to a tube *i* extending across the press and caused to run up and down rails *j* as the lever *g* is rocked. The lever *g* is connected by a shaft *k* to a similar lever on the other side of the press which in turn is similarly connected to the other end of the tube *i* by a link *h*. The tube is provided with nozzles *l* and carries at each of its ends 40 a valve casing *m* in which two valves *n* and *o* are mounted, the central part of the casing being closed by a plug. The valves are connected by flexible pipes or hose *p* with a vacuum chamber *S* in which vacuum is 45 maintained by a pump *P*. Both valves are operated by a three armed lever *q*, the longest arm of which strikes against stops *r* and *s* while the short arms of the said lever depress the valves. A catch not shown serves to normally hold the valves in their

open position. The stops *r* are stationary while the stops *s* are so connected with the link and lever gearing for actuating the press that they come out of the path of the valve lever *q* when the press is thrown off. 60

In front of the pile of sheets the open ends of two pipes *t* are arranged from which air under pressure is blown against the front of the pile the outflow of such air being controlled by the valve *u* which is operated by stops *v* and *w* in a manner similar to that described with reference to the valves *n* and *o* and normally held in its open position by a catch not shown. The valve lever *x* is mounted on an eccentrically journaled 70 pin and is brought out of the path of the stops *v* and *w* by turning the said pin in its journals. The said pin is connected by link and lever mechanism *y*, *y'* with the throw-off gearing of the press, so that the valves *u*, *n* and *o* are thrown out of action simultaneously. The valve *u* is connected by a flexible pipe or hose *z* with a chamber *D* supplied with air under pressure by the pump *P*. The chambers *D* and *S* must be 75 provided for reducing the variations of pressure due to the unequal number of revolutions of the press and the pump. 80

The valves *n* and *o* may be alternately connected with the chamber and the pump 85 through a cock *H'* or with the pump only after turning the cock through an angle of 90 degrees. In the cock *H'* a safety valve *a'* is provided which is connected either with the atmosphere or with the chamber 90 according to the position of the cock. In operation the cock is in the position I and during starting in the position II. In the former case the pump draws air from the chamber *S* and from the pipes *p* simultaneously. When the vacuum becomes too high the valve *a'* opens inwardly thus permitting air to enter. During starting the cock is in the position II. In this position the pump 95 *P* can communicate with the chamber *S* only after the valve *a'* has been opened so that when the vacuum becomes too high in the pipe *p* air is drawn from the chamber. The valve *u* can be connected by the cock *H'* alternately with the chamber *D* and the 100 pump. In this cock a safety valve *b'* is provided which when the pressure becomes too high permits air to escape into the atmosphere in the position I and to enter into the chamber in the position II. 105 110

The lower ends of the rails j are pivoted so their upper ends can be raised and lowered by levers c' . One of the levers c' is a double armed one and carries at its other end a roller or bowl engaging the periphery of the crank disk e and is connected with the other lever c' by a shaft d' . Before the tube i reaches its uppermost position the levers c' are raised so that the 5 said tube comes with its nozzles just above the front edge of the pile. Just before the tube arrives in this position the valves n are opened by the stops s thus connecting the interior of the tube i with the chamber 10 S through the pipes p , in which chamber vacuum is maintained by the pump P . Consequently air flows into the tube through the nozzles l and the uppermost sheet is taken up by and held against the ends of 15 the nozzles by the pressure of the atmospheric air. As the rails j continue their movement the tube i slides downward carrying with it the sheet. In order that the sheet taken up may be firmly held the valves 20 n are held in the open position during this movement by a catch not shown.

Just before the tube i reaches its lowermost position the catch is released by the stops r and immediately thereafter the 25 valves o are opened admitting air into the tube and the sheet is dropped.

During the following upward movement of the tube i the valves o are kept open until the tube has nearly reached its uppermost 30 position then the catch is released by the stops s and the valves a are opened and the series of operations just described is repeated.

As the successive sheets have to be fed in 35 the same manner the relative position of the pile and the tube i must remain unaltered. In order to secure this the table e' is raised after the removal of a sheet, a distance equal to the thickness of a sheet. 40 The tables e' are suspended on screws f' f^2 f^3 f^4 actuated by worm wheels g' g^2 g^3 g^4 g^5 g^6 g^7 g^8 and ratchet wheels h' h^2 . The screws are journaled on top in the transverse beam b and at their lower ends in 45 brackets on the standards a . The nuts of the outer screws are mounted in the frames i' and the nuts of the inner screws are in the worm wheels g^4 g^6 . The tables e' are 50 adapted to move transversely on the frames i' by means of the shafts j' and cams k' . The worm wheels are rigidly connected with the ratchet wheels and are operated by link and lever gearing l' from the shaft K . The ratchet wheels and the worm wheels g' g^2 55 g^5 and g^7 are fixed on hollow shafts m' threaded on the shaft c . The shafts m' may be connected with each other in the middle by a clutch not shown. If the two tables e' carry paper of different thickness such 60 65 tables must be raised at different speeds. In

this case the ratchet wheels must be operated at different speeds. Also the vacuum and the pressure of the air must be regulated to suit the different thickness of the paper. The two central screws f^2 f^3 may be 70 removed and the two tables and the hollow shafts may be connected with each other and the ratchet wheels may be adjusted for the same speed if it is desired to print on sheets of double size. 75

The following are the advantages of our improved pile feeder over similar old constructions: The present invention provides an apparatus which may be simply and readily mounted in position and which is 80 independent of the construction of the press and which can be operated by small pumps running at a higher speed than the press. By using the hollow shafts the space above the press is less encumbered because the table 85 shaft mounted in the old constructions at the side of the driving shaft is in the present apparatus mounted on the said driving shaft. In the same way on the shaft d' connecting the two levers c' another shaft 90 required for controlling purposes may be mounted. By the worm wheel gearing we are enabled to provide screw spindles within the table and further to easily vary the distance of the shaft c from the shaft k so 95 that it may suit the lever stroke required at any time without otherwise changing the construction. By using the worm wheels we are further enabled to raise the two halves of the table independently the one 100 of the other. Mounting the controlling valves directly on the suction tube offers the advantage that it is only the comparatively small tube that has to be evacuated for feeding each sheet whereas in the old construction a long pipe system or even the entire space up to the pump piston had to be evacuated which involves a considerable loss of power. By the arrangement of two vacuum valves on both ends of the suction tube the 105 further advantage is obtained that with large sheets and high printing speeds the suction is uniform and comes into action at the same moment over the entire suction tube whereas with the usual arrangement 110 of the valve at one end only of the suction tube it may happen that this tube catches hold of the sheet at the end near the valve faster than at the other ends which results 115 in an irregular feeding of the sheet. 120

The same is true with the destruction of vacuum. With one air admission valve at one end only of the tube, the sheet seized is liable to be released at one side earlier than at the other side under the above named 125 conditions and therefore to assume an incorrect position relatively to the register pins. By connecting the stops s with the throw off gearing of the press we avoid that a sheet can be seized and fed after throw- 130

ing off the press, whereas with the known apparatus it may happen that a sheet seized is not released on throwing off the press and is torn to pieces in being continued to be fed. By operating the lever x in the manner above described we avoid that the valve u is opened and air under pressure is consumed after throwing off the press.

By connecting the cocks H' H^2 with the throw-off gearing of the press the result is secured that sheets are fed at the first revolution of the press, as by the direct connection of the valves n and u with the pump, the vacuum or air under pressure required is produced at once while on the other hand at the same time the vacuum and pressure chambers are prepared for the regular operation of the apparatus, vacuum being produced and air under pressure being accumulated respectively in the said chambers. In the so-called stop cylinder presses it must never happen that the press operates without a sheet being interposed. If now a pump not running in synchronism with, the press is used, this might happen in starting the press if there be not sufficient vacuum in the vacuum chambers as will be the case when the press has been stopped for some time. The same is true of the chamber for air under pressure.

Claims:

1. In a pneumatic pile feeder the combination of a feeding tube, valves for controlling the admission of air into such tube and the suction conduits connected with such tube, such valves being located at both ends of the said feeding tube, link and lever mechanism adapted to be connected with the throw off gearing of the press, stops connected with such link and lever gearing and adapted to actuate the said valves controlling the suction conduits whereby on throwing off the press the said stops are brought out of engagement with the said valves, and means independent of the said link and lever gearing and adapted to actuate the air admission valves on the feeding tube.
2. In a pneumatic pile feeder the combination of a feeding tube, valves for controlling the admission of air into such tube and the suction conduits connected with such tube, such valves being located at both ends of the said feeding tube, link and lever mechanism adapted to be connected with the throw off gearing of the press, stops

connected with such link and lever gearing and adapted to actuate the said valves controlling the suction conduits whereby on throwing off the press the said stops are moved out of the path of the said valves, and levers journaled on eccentrically journaled pins for actuating the air admission valves and actuated by said stops, the said levers being connected with the said throw off link and lever mechanism.

3. In a pneumatic pile feeder, the combination of an air pump, a vacuum chamber, a chamber for accumulating air under pressure, pipes connecting the air pump with the said chambers and automatic valves in such pipes, substantially as and for the purpose described.

4. In a pneumatic pile feeder, the combination of an air pump, a vacuum chamber, a chamber for air under pressure, pipes connecting the air pump with the said chamber, cocks interposed in such pipes and an automatic safety valve mounted in each of such cocks substantially as and for the purpose described.

5. In a pneumatic pile feeder, the combination of an air pump, a vacuum chamber, a chamber for air under pressure, pipes connecting the air pump with the said chambers, cocks interposed in such pipes, an automatic safety valve mounted in each of such cocks, a feed-tube, valves for controlling the admission of air to the said tube, and a link and lever mechanism adapted to be connected with the throw off gearing of the press and from which the said valves are operated, substantially as and for the purpose described.

6. In a pneumatic feeder, the combination of a suction tube, suction means to create a vacuum in the tube, air inlet and outlet valves commanding the tube, means to actuate the valves in succession and means adapted to be connected with throw-off mechanism of the press arranged to throw the said valve-actuating means out of action.

In testimony whereof, we affix our signatures, in presence of two witnesses.
